TWISTER CAP

Lavern J. Jordan, Fairview, Richard F. Bergmann, Lakewood, and Alden H. Burkholder, Cleveland, Ohio, assignors to Industrial Rayon Corporation, Cleveland, Ohio, a corporation of Delaware

Application June 3, 1941, Serial No. 396,420

12 Claims.

(Cl. 57—127)

This invention relates to caps for use in cap-twisting apparatus of the kind employed in twisting thread or the like.

In the operation of cap-twisting apparatus, the thread or the like to be twisted is drawn from a suitable source, through a thread guide disposed above the apparatus, around the lower edge of the twister cap, and onto a rotating bobbin. In passing between the thread guide and the lower edge of the cap, the thread travels about the outside of the cap in what is known as a "balloon." Twist is imparted to the thread by rotating the bobbin, the amount of twist being proportional to the ratio between the angular speed of the bobbin and the linear speed of the thread as it leaves the source.

When the twisting operation is first begun; i. e., with the bobbin empty, the thread travels about the cap in a path bowed laterally outward from the side of the cap but otherwise extending substantially vertically downward from the thread guide to the edge of the cap. At the start of the winding operation, especially in the case of thread of low denier, the thread may be and frequently is in actual contact with both the upper and lower edges of the cap. From the lower edge of the cap to the bobbin, the thread describes a path tangent to the surface of the bobbin in a plane perpendicular to its axis of rotation.

As the bobbin fills, the thread path becomes progressively more bowed, particularly in the vicinity of the upper edge of the cap. At the same time, the path of the thread between the thread guide and the lower edge of the cap assumes an increasingly pronounced spiral form imposed by relative lateral displacement of the upper and lower portions of the thread path. By the time the bobbin is full, the thread is in effect wrapped around the lower end of the cap, being in contact with the side of the cap for several inches above the edge thereof.

In the meanwhile, the angle between the length of thread passing from the edge of the cap to the surface of the bobbin and an imaginary tangent to the cap at the point where the thread passes under the edge of the cap becomes progressively smaller. As the angle is decreased, the component of force operating to cause the balloon to rotate about the cap is increased with the result that less tension exists in the balloon; as a matter of fact, it is in consequence of this state of affairs that the balloon tends to bow farther outward from the upper edge of the cap. In this respect, the problem of winding the

thread onto the bobbin offers difficulty only because the contact between the thread and the side and lower edge of the cap is increased to such a degree as to cause a drag in the thread itself.

Inasmuch as considerable friction is developed as the thread moves around the cap, the part or parts thereof coming into contact with the thread are subject to relatively rapid wear. For this reason it has been considered advisable heretofore to employ for the parts of the cap in contact with the thread a metal or other material capable of taking on a high polish, this in order to reduce the amount of friction developed by passage of the thread over the surfaces of the cap. But time and expense are involved in keeping such metal surfaces clean; moreover, when the side of the caps is of metal, the caps are cumbersome and costly to manufacture. They do, of course, have the important advantage of being rigid in construction.

Heretofore, most twisting operations have been performed in buildings, rooms or areas not employed in the thread-forming operations, in which case the problem of corrosion is of no particular consequence. Where, however, the twisting operation is performed as a part of a continuous sequence of operations immediately after the production of artificial silk thread; for instance, as shown in Patent 2,225,642, the atmosphere in the twisting area may be of high humidity. Under such conditions, the metallic parts of the cap tend to corrode; consequently, when multiple-filament artificial silk thread is passed over the corroded surfaces, the individual filaments thereof become abraded or snagged, impairing the quality of the thread.

If the surfaces of the cap coming into contact with the thread are coated with a protective material; e. g., paint, such material is soon worn away by the passage of the thread thereover. It is worn away even more quickly when, as is often the case, it is a pigmented thread that is being twisted. In either case, even if a metal capable of taking on a high polish be employed, it will in a short time become pitted or otherwise roughened by the action of the thread itself, thus bringing about results similar to those obtained when corroded caps are continued in use.

For these reasons, the characteristics of the materials employed in the construction of the cap are of great importance.

In apparatus of the kind disclosed in Patent 2,225,642, as many as 10,000 cap-twisting units may be employed simultaneously in a single

plant. When it is desired to remove a completely filled bobbin from one of these units, the operator grasps the top of the twister cap with one hand, removing it from the spindle assembly by lifting it upward. With the other hand he grasps the top of the filled bobbin, removes it from the spindle assembly, places it in a rack, and replaces it with an empty bobbin. This done, he replaces the twister cap. Since the operator continues to hold the twister cap in the same hand throughout these operations, it is desirable to employ a cap that is light in weight; however, it is no less important that the cap be rigid.

In order to keep down the weight of the cap, it should obviously be as small as possible. Where, however, the amount of thread being twisted in one length is an important factor, it is necessary to wind a package as large as possible at the highest practicable speed. In such circumstances, a two-fold desideratum is presented; viz., keeping the twister cap as small as possible while winding the largest possible thread package.

The necessary combination of rigidity, light weight and satisfactory wearing qualities is to be found in the cap of the present invention, which cap is highly resistant to corrosion, strongly constructed, yet very light in weight. The surfaces of the cap in contact with the thread are so constructed as to reduce to a minimum the frictional drag upon the yarn passing thereover.

The cap as a whole, including the parts thereof coming into contact with thread, is of materials which are particularly adapted to use in cap-twisting apparatus operated in a humid atmosphere.

Without intending to limit the invention thereto, a particularly satisfactory embodiment of the invention is illustrated in the accompanying drawing. Figure 1 is a sectional elevation of a portion of a cap-twisting apparatus showing the twister cap of the present invention, the bobbin, and the parts of the spindle assembly normally associated therewith. Figure 2 represents a side elevation of the apparatus from line 2-2 of Figure 1. Figure 3 is a portion of the sectional elevation of Figure 1 on a greatly enlarged scale, the portion being from the lower edge of the cap.

As shown in Figure 1, the apparatus as a whole comprises a stationary spindle shaft 1 surrounded by a sleeve 2 capable of reciprocating lengthwise of spindle shaft 1, the sleeve being shown in its uppermost position. A collar 3 fixed to sleeve 2 serves to carry rotary whorl 4 and bobbin support 5. Bobbin 6 is mounted on support 5, rotational movement from a belt (not shown) being transmitted thereto by means of whorl 4 and support 5. Thus while spindle shaft 1 remains stationary, sleeve 2 can reciprocate vertically and whorl 4, support 5 and bobbin 6 can rotate about sleeve 2 as it reciprocates.

Cap 7 is mounted in the usual way on the upper end of spindle shaft 1 in such manner that the movable parts of the spindle assembly can reciprocate and rotate within the cap.

The cap itself includes a boss 8 to which is attached a dome 9, such dome serving to support skirt 10. Ring 11 is attached to the lower end of skirt 10 to guide the thread A in the manner hereinafter explained as it is being wound in package form on bobbin 6. Boss 8 has formed therein a tapered bore 16 which seats cap 7 upon tapered surface 17 of spindle shaft 1 to hold the cap in place, the weight of the cap being sufficient to hold it on the spindle

shaft. Preferably boss 8 is made of metal sufficiently malleable to permit the formation of lip 15 by swaging the boss at the end thereof. Conveniently, dome 9 may be made of pressed steel, cast metal or other material which may be formed into the desired shape with relatively little working.

Skirt 10, which depends from dome 9, is held in place by cooperation of an annular groove 19 formed in the inner surface of skirt 10 with an annular ridge 18 formed on the outer surface of dome 9. Shoulder 21 on dome 9 and shoulder 22 on skirt 10 also assist in holding the parts of the cap in assembled relation, particularly if a cementitious material is employed to bind the parts together. Such a construction makes it possible to assemble and disassemble the cap with ease and rapidity.

Skirt 10 is of laminated construction, being made of a synthetic plastic such as "Bakelite" which is reinforced with sheets of fiber, cloth, paper or other suitable material. One laminated plastic of this type is sold under the trade-name "Micarta." Such materials not only are resistant to corrosive fumes but take on a high polish which is maintained during and in some cases even improved with use. Since, according to the present invention, no thread comes into contact with boss 8 or dome 9, both of the latter may be painted with lacquer or otherwise coated to prevent corrosion.

Ring 11 is fitted on the end of skirt 10, shoulder 23 on skirt 10 serving to locate ring 11 on said skirt; preferably, ring 11 is cemented to the skirt 10.

Inasmuch as the greatest wear takes place where the thread passes around the edge of ring 11, such ring is preferably made of a high grade stainless steel such as the hardened nickel-free chrome alloy steel known in the trade and under SAE specifications as "stainless steel alloy 420" or "Carpenter 2" stainless steel. This alloy, which is of the same quality as high grade cutlery steel, is not only capable of being hardened but of taking on a high polish. An analysis of this alloy shows that it contains about .30% carbon and about 13.00% chromium. In lieu thereof, various other alloys which are equally or more resistant to abrasion may be employed.

As appears from Figure 3, ring 11 is beveled to provide a definite relationship between outer surface 24 and inner surface 25, arc 26 serving to join the two surfaces. Preferably inner surface 25 is at an angle of approximately 30° to outer surface 24. Arc 26 is tangent to both outer surface 24 and inner surface 25. The radius of arc 26 should be less than .01 inch when the twister cap on which it is mounted is approximately ten inches long and five inches in diameter and the collecting bobbin on which the thread is being wound is approximately 2 1/4 inches in diameter. This radius serves adequately for thread having a denier as low as or lower than one hundred.

The radius of the arc joining the beveled inner surface 25 of ring 11 with the outer surface 24 thereof is determinative of the path of the thread in the balloon, this following from the fact that, by decreasing the tension in the thread, the reduced radius allows the thread to be bowed farther outward from the cap.

If, because of rapid wear, the radius changes within a relatively short time, the critical character of such radius becomes even more critical. With a hardened steel alloy of high quality, it is possible to machine the rings down to a toler-

ance of less than plus or minus a thousandth of an inch at a radius ranging from .003 to .008 inch. Rings thus machined will retain the desired radius for a long period of time notwithstanding the considerable amount of abrasion to which they are subjected.

When thread of 100 denier, 40 filaments, is being twisted, the preferred radius of the arc 26 is approximately .005 inch, plus or minus .002 inch. The diameter of the empty bobbin should in such case be approximately 2 $\frac{3}{4}$ inches. Under these conditions, the balloon will completely miss the upper portion of twister cap 7 from the very start of the winding operation, being far enough from the upper edge of the cap to be free from contact therewith even in the twisting of thread of low denier. This is due to the relatively low tension in the thread between the edge of the ring and the surface of the collecting bobbin, as well as between the lower edge of the cap and the thread guide above the cap.

At the same time, the tension in the thread between the lower edge of the cap and the periphery of the bobbin is substantially reduced.

The apparatus of the invention is particularly suitable for use in high speed winding operations. For instance, when the thread to be twisted passes from the source at a linear speed of approximately 76 meters per minute, the bobbin upon which the thread is collected is rotated at an angular velocity of approximately 8,000 revolutions per minute. This imparts a twist of approximately two and one-half turns per inch to the thread. Operations at such high speed necessitate apparatus which is durable and yet efficient in operation; these requirements the apparatus of the present invention amply satisfies.

The twister cap illustrated in the drawing represents the preferred embodiment of the invention as it is employed in the twisting of pigmented thread at comparatively high speeds. However, modifications as to construction and use of materials may be made without departing from the spirit of the invention. Skirts made according to the invention may be constructed of plastic material which has sufficient strength in and of itself without laminae incorporated therein; also, the ring may be made of other types of wear-resistant material than that described herein. For instance, if the apparatus is not operated in an atmosphere of high humidity, etc., a wear-resistant metal not necessarily of the stainless steel variety may be employed.

It is intended that the patent shall cover, by suitable expression in the appended claims, whatever features of patentable novelty reside in the invention.

What is claimed is:

1. A twister cap comprising a metal dome; a non-metallic skirt attached to said dome; and, attached to the lower end of said skirt, a beveled ring of wear-resistant material, the inner and outer surfaces of said ring being joined by an arc tangent to both of said surfaces.
2. A twister cap comprising a metal dome, said dome including a mounting boss; a substantially cylindrical non-metallic skirt attached to said dome; one or more annular ridges adjacent the lower edge of said dome; one or more annular grooves adjacent the upper edge of said skirt, said grooves cooperating with said ridges to hold said dome and said skirt in assembled relation; and a wear-resistant ring mounted at the lower edge of said skirt.
3. A twister cap comprising a metal dome; a non-metallic skirt attached to said dome; and a hardened metal ring mounted at the lower edge of said skirt.
4. A twister cap comprising a metal dome; a substantially cylindrical molded plastic skirt; and, mounted at the lower end of said skirt, a hardened metal ring.
5. A twister cap of the character described in claim 4 wherein the skirt is made of plastic material having a non-metallic reinforcing material incorporated therein.
6. A twister cap of the character described in claim 4 wherein the ring is made of a hardened steel alloy.
7. A ring for twister caps comprising a beveled annular ring, the inner and outer surfaces of said ring being joined by an arc having a radius not greater than .01 inch.
8. A ring of the character described in claim 7 which ring is made of a hardened, nickel-free, stainless steel alloy.
9. A ring of the character described in claim 7 in which the inner and outer surfaces thereof are inclined to each other at an angle of approximately 30°.
10. A ring of the character described in claim 7 in which the arc is tangent to at least one of said surfaces.
11. A ring of the character described in claim 7 in which the radius of the arc is from .003 to .008 inch.
12. A ring of the character described in claim 7 made from material having substantially the properties of SAE stainless steel alloy 420.
